UNITED STATES PATENT OFFICE.

HARRY M. STEPHENSON, OF DENVER, COLORADO.

AUTOMATIC TAPE OR FILM REVERSING REEL.

Application filed September 27, 1919, Serial No. 326,852. Renewed June 4, 1923.

To all whom it may concern:

Be it known that I, HARRY M. STEPHENSON, a citizen of the United States, residing at the city and county of Denver and State 5 of Colorado, have invented certain new and useful Improvements in Automatic Tape or Film Reversing Reels, and do declare the following to be a full, clear, and exact description of the invention, such as will enable others skilled in the art to which it 10 pertains to make and use the same, reference being had to the accompanying drawings, and to the characters of reference marked thereon, which form a part of this specification. 15

This invention relates to devices for winding film after use, and is especially designed in the present showing for winding motion picture films as they leave the projecting machine; but it may be used also for winding tapes or the like on player pianos or similar instruments.

The object of the invention is to so wind the film after use, that it may be immediately returned for reuse without rewinding to present the beginning of the film at the outer part of the reel. This application constitutes an improvement over that filed by me August 28th, 1919, Serial No. 320, 30 380.

Briefly, the invention comprises a stationary casing having therein a rotary carrier, on which is mounted a reel for internal winding of the film, the carrier having 35 movable devices to engage the film as it is wound and adapted to be lifted as they pass the incoming portion of the film. The casing has a cover carrying a film guide and means to position the film as it is wound onto the 40 reel. The particular improvements in this application lie in the device for positioning the incoming film, the specific operating means for the devices which engage and hold the film after being wound, and the means 45 for determining the pressure of said engaging devices upon the film. The positioning means comprises a plurality of small rollers on stationary axes, said rollers being so tapered and so positioned as to give the proper direction to the film which comes vertically to the reel and is then diverted at an angle as it passes into the reel. The devices for engaging and holding the posi-

tioned film constitute pivoted arms provided with meshing bevel gears. The means for 55 determining the pressure of said engaging devices comprises a ring carried upon rollers at the periphery of the carrier and frictional means secured in the casing wall and bearing against said ring. The ring 60 has connection by means of cables with the film-engaging devices. As the carrier rotates, the tendency of the ring is to rotate with it, but engagement of the friction devices on the ring retards its motion somewhat and transmits a pull upon each of the film-engaging devices through the respective cable. In the drawing:

Fig. 1 is a vertical section through the assembled device with a film descending into 70 the reel.

Figs. 2 to 7, inclusive, represent an exploded view of the entire structure.

Fig. 2 is a vertical section through the cover and slide with the film guide omitted. 75

Fig. 3 is a vertical section of the rim of the reel.

Fig. 4 is a vertical section of the back plate of the reel, showing slots therein.

Fig. 5 is a vertical section of the carrier 80 with the film-engaging devices and the friction ring thereon.

Fig. 6 is a vertical section of the casing and also the friction pads which engage the ring. 85

Fig. 7 shows the pulley for driving the carrier.

Fig. 8 is a view of the back of the casing.

Fig. 9 is an inside view of the pulley, showing the ratchet thereon. 90

Fig. 10 is a rear view of the carrier with assembled parts, taken from the line 10—10 of Fig. 5.

Fig. 11 is an enlarged detail showing of the means for operating the film-engaging 95 devices, this view looking in the same direction as that of Fig. 10.

Fig. 12 is a face view of the carrier with the back and rim of the reel in position, the friction ring being omitted.

Fig. 13 is an enlarged sectional detail on the line 13 of Fig. 12. 100

Fig. 14 is an enlarged elevational detail from the line 14 of Fig. 12.

Fig. 15 is an enlarged sectional detail on 105 the line 15 of Fig. 12.

Fig. 16 is a face view of the cover or door for the carrier.

Fig. 17 is a face view of auxiliary parts for the reel, upon which the film is mounted 5 after removal from the machine.

Fig. 18 is a cross section, showing the auxiliary parts of Fig. 17 assembled with the back plate of the reel shown in Fig. 4.

The casing comprises a back 20 and a 10 rim 21, the back having an integral external bearing 22 to receive the drive shaft 23, which carries a pulley 24 having ratchet teeth 25 engaged by a dog 26, secured upon the bearing 22. A hub 27 on the carrier 28 15 fixedly receives the drive shaft 23. The hub 27 bears upon an internal boss 122 upon the casing back 20. The carrier 28 is provided with an annular shoulder 29, forming a circular pocket, and a second annular 20 shoulder 30, forming a larger circular pocket. The smaller pocket receives the reel back 31, which has an integral hub 32, provided with a bayonet slot 33, for purposes hereinafter described.

25 The larger pocket formed by the shoulder 30 receives the flange 34 of the reel rim 35. The reel back 31 is held against rotation by means of pins 36 in the carrier 28, which project through apertures in the reel back, 30 and the reel rim 35 is held in its pocket 35 against rotation by means of pins 37 (of which three are shown), which project into apertures formed in the flange 34. The flange 34 overlaps the reel back 31 slightly 40 when in operative position, thereby retaining the back 31 in position while a lug 38 on the bottom of the carrier, and a latch 39 on the top of the carrier, controlled by a spring 40 (Fig. 12), retain the rim 35 in its 45 pocket. The rim 35 is composed of two parts hinged at 41 and adapted to be fastened opposite the hinge 41 by means of a spring clip 42 on one half of the rim which engages a pin 43 on the other half of the rim.

50 The cover or door 50 is hinged to the casing, as shown, and carries a slide 51 retained in position by guides 52, secured to the cover. The cover is provided with an elongated slot 53, and the slide with a shorter slot 54, these slots accommodating a bracket 55 held against rotation on pins 56 extending through a bracket 57 secured to the slide 51. Tapered rollers 58 are mounted between the plates of the bracket 55, and are 55 so positioned as to guide the film F, which enters through the film guide 59 into proper position within the reel 35. The taper of the rollers 58 may be varied in order to give the film proper changes in direction as it enters 60 the reel. The film guide 59 is secured by means of a brace 60, connected with the slide 51. In order to provide the proper amount of pressure of the rollers 58 upon the incoming film, and at the same time 65 allow the rollers to rise as the film builds

up, there is provided a spring 61 connected with the cover 50 and with an arm 62, secured to the slide 52. A toothed bar 63 is also secured to the slide 51 and is engaged by means of the dog 64, which means positively holds the slide in position as it rises. 70

In order to properly retain the film, as each convolution builds up with the reel 75 35, fingers 72, mounted on the carrier, are provided, these fingers projecting through slots 71 in the carrier and through slots 70 in the reel back, the projecting end of each finger being provided with a pad for engagement with the film. Each finger is 80 slidably mounted upon a slotted plate 73, secured to the back of the carrier, by means of a block 74, in which the respective finger 72 is pivoted. The finger pivot 75 carries a bevel gear 76, which meshes with a second bevel gear 77 on a spindle mounted in 85 brackets 78, also on the block 74. The spindle carries a laterally projecting arm 79, equipped at its outer end with a roller, 80, adapted to engage a cam roller 81 in the lower part of the casing, whereby, through 90 the medium of the bevel gears 76 and 77, each finger 72 is lifted from engagement with the film as it passes the incoming portion of the film, and the positioning rollers 58. This operation is indicated in the lower 95 part of Fig. 1.

In order to restore each finger 72 to film-engaging position, after passing the incoming film portion, a spring 82 (Fig. 11) is provided, this spring being connected with 100 one of the brackets 78 and with the spindle of the bevel gear 77.

Each block 74 has connected thereto a cable 83, which passes over a pulley 84, mounted adjacent the periphery of the carrier 28, and thence to a pin 85, mounted in an annular friction ring 86, carried upon rollers 87, secured also to the carrier 28, adjacent its periphery and preferably upon the same pivot pin as the pulley 84. 110

Oppositely disposed friction pads 90 secured to blocks 91, pressed by springs 92 on pins 93, secured in the casing, bear upon the friction ring 86. As the carrier rotates, the tendency of the ring 86 is to rotate with 115 it but friction of the pads 90 upon the ring 86 produces a drag thereon and results in a partial reverse motion of the ring 86 upon the rollers 87. This imparts a pull to each cable 83, which is transmitted to the blocks 120 74, and thence to the film-engaging fingers 72. This tends to pull the fingers 72 outwardly toward the periphery of the carrier and produce sufficient contact of the fingers 125 with the film within the reel 35.

It should be noted that in order to properly position and maintain the pressure of the fingers 72 upon the film, the combined tension of the springs 82 exceeds the pull produced by the friction means 90 upon the 130

annular friction ring 86. In this manner, proper pressure of the finger 72 upon the film is obtained without unduly drawing the block 74 toward the periphery of the carrier.

5 By this construction the fingers 72 and their blocks 74 are permitted to move inwardly as the film builds up within the reel 35.

When the film has been wound within the reel 35, the door 50 is opened, carrying with it the slide 51, positioning rollers 58, and the film guide 59. The auxiliary reel portions of Figs. 17 and 18 are then inserted to assume the position with relation to the reel back 31, as shown in Fig. 18, the film, however, being omitted in Fig. 18, for clearness.

This auxiliary structure comprises a plate 100 of the same size as the reel back 31, this plate 100 being provided with radially disposed slots 101.

20 A second plate 102, provided with curved slots 103, is superposed on the plate 100, and the stems of pins 104 project through the slots 101, 103, the pins 104 being secured by means of heads 105. A sleeve 106 is axially disposed in the plates 100, 102, and is pressed outwardly by means of springs 107. The inner end of the sleeve 106 is provided with an inwardly projecting pin 108, this pin being adapted to engage and seat within the bayonet slot 33 of the hub 32 on the reel back 31. To remove the film, the pins 104 are positioned within the film and between the fingers 72. The plate 102 is then turned to move the pins 104 outwardly in the slots 101, 103, until they engage firmly with the film. The sleeve 106 is then pressed inwardly to cause the pin 108 to enter the bayonet slot 33 and seat in the inner end thereof, whereby the parts are retained in position under the tension of the

35 springs 107.

The latch 39 at the top of the carrier is then released, and the top of the reel tipped forward until the reel back 31 and flange 34 are withdrawn from their pockets, the reel then being lifted from behind the lug 38 at the bottom of the carrier.

40 The latch 42 is then opened and the parts of the rim 35 are then swung on the pivot 41 to remove them from the reel thus formed by the reel back 31 and the plate 100.

The sleeve 106 is provided with a bearing 109, with a diameter equal to that of the hub 32 on the reel back 31. These parts 32 and 109 then constitute a positive bearing 45 for a spindle by means of which the reel may be mounted in a motion picture projecting machine.

40 In order to prepare the carrier 28 to wind another film, another reel back 31 is placed in position, the rim 35 reassembled and placed in position, the door 50 is closed, the film is passed down through the guide 59, and secured in any suitable manner to the rim 35 through the opening 150 in the door, as shown in Fig. 16.

From the foregoing, it is believed that the construction and operation of this invention will be clear.

I claim:

1. An automatic tape- and film-reversing reel, comprising a support, a rotary reel carrier on said support, a reel for internal winding of the tape or film mounted to rotate with the carrier, a plurality of fingers slidably and pivotally mounted on the carrier and having one end of each projecting within the reel to engage the film being wound therein, and means tending to draw said fingers bodily outward, comprising a member mounted on the carrier for relative movement thereon, friction means on the support engaging said member, and means connecting said member with said fingers. 70

2. An automatic tape- and film-reversing reel, comprising a support, a rotary reel carrier on said support, a reel for internal winding of the tape or film mounted to rotate with the carrier, a plurality of fingers slidably and pivotally mounted on the carrier and having one end of each projecting within the reel to engage the film being wound therein, and means tending to draw said fingers bodily outward comprising a ring mounted on the carrier for relative movement thereon, friction devices on the support engaging said ring, and means connecting said member and ring with said fingers. 85

3. An automatic tape- and film-reversing reel, comprising a support, a rotary reel carrier on said support, a reel for internal winding of the tape or film mounted to rotate with the carrier, a plurality of blocks slidably mounted on said carrier, a finger pivotally mounted on each block, having one end projecting within said reel to engage the film, a bevel gear on the other end of said finger, a spindle pivoted on each block, a beveled gear on one end of each spindle and meshing with the other bevel gear, and a cam on said support in the path of the other end of each spindle to be engaged thereby and reciprocate said projecting end of each finger. 100

4. An automatic tape- and film-reversing reel, comprising a support, a rotary reel carrier on said support, a reel for internal winding of the tape or film mounted to rotate with the carrier, a plurality of blocks slidably mounted on said carrier, a finger pivotally mounted on each block, having one end projecting within said reel to engage the film, a bevel gear on the other end of said finger, a spindle pivoted on each block, a beveled gear on one end of each spindle and meshing with the other bevel gear, a cam on said support in the path of the other end of each spindle to be engaged thereby and reciprocate said projecting end of each finger, means tending to draw said fingers 115

120

125

130

4
bodily outward comprising a member mounted on the carrier for relative movement thereon, friction means on the support engaging said member, and means connecting said member with said fingers.

5. An automatic tape- and film-reversing reel, comprising a support, a rotary reel carrier on said support, a reel for internal winding of the tape or film mounted to rotate with the carrier, a plurality of blocks slidably mounted on said carrier, a finger pivotally mounted on each block, having one end projecting within said reel to engage the film, a bevel gear on the other end of said finger, a spindle pivoted on each block, a beveled gear on one end of each spindle and meshing with the other bevel gear, a cam on said support in the path of the other end of each spindle to be engaged thereby and reciprocate said projecting end of each finger, and means tending to draw said fingers bodily outward, comprising a ring mounted on the carrier for relative movement therein, friction devices on the support and engaging said ring, means connecting the said ring with the said finger.

6. In an automatic tape- and film-reversing reel, comprising a support, a carrier mounted to rotate therein, the carrier having an annular shoulder forming a pocket, a reel back mounted in said pocket, a reel rim mounted on said carrier, and means to retain the rim in position on the carrier.

7. In an automatic tape- and film-reversing reel, comprising a support, a carrier mounted to rotate on said support, said carrier having an annular shoulder forming a pocket for a reel back and also having a second shoulder forming a larger pocket for a reel rim, and means on the carrier to retain the rim in position.

8. In an automatic tape- and film-reversing reel, a support, a carrier, said carrier having an annular shoulder forming a pocket, a reel back mounted in said pocket, said carrier having a second shoulder forming a larger pocket, a reel rim mounted in said larger pocket and overlapping said back sufficiently to retain the back, and means to retain the rim in position on the carrier.

9. In an automatic tape- and film-reversing reel, a support, a carrier, said carrier having an annular shoulder forming a pocket, a reel back mounted in said pocket, said carrier having a second shoulder forming a larger pocket, a reel rim mounted in said larger pocket and overlapping said back sufficiently to retain the back, means to retain the rim in position on the carrier, an auxiliary reel plate, movable pins mounted on said plate, and means to connect said plate with said reel back.

10. In an automatic tape- and film-reversing reel, a support, a carrier, said carrier

having an annular shoulder forming a pocket, a reel back mounted in said pocket, said carrier having a second shoulder forming a larger pocket, a reel rim mounted in said larger pocket and overlapping said back sufficiently to retain the back, means to retain the rim in position on the carrier, an auxiliary reel plate, movable pins mounted on said plate, and means to connect said plate with said reel back, said reel rim being jointed for removal from said reel back and auxiliary plate.

11. In an automatic tape- and film-reversing reel, a support, a carrier, said carrier having an annular shoulder forming a pocket, a reel back mounted in said pocket, said carrier having a second shoulder forming a larger pocket, a reel rim mounted in said larger pocket and overlapping said back sufficiently to retain the back, means to retain the rim in position on the carrier, an auxiliary reel plate, movable pins mounted on said plate, and means to connect said plate with said reel back, said reel rim being jointed for removal from said reel back and auxiliary plate, said back having an axial bearing and said plate having an axial member thereon to engage said bearing.

12. In an automatic tape- and film-reversing reel, a support, a carrier, said carrier having an annular shoulder forming a pocket, a reel back mounted in said pocket, said carrier having a second shoulder forming a larger pocket, a reel rim mounted in said larger pocket and overlapping said back sufficiently to retain the back, means to retain the rim in position on the carrier, an auxiliary reel plate, movable pins mounted on said plate, and means to connect said plate with said reel back, said reel rim being jointed for removal from said reel back and auxiliary plate, said reel back having axial bearing, said plate having an axial member and a bearing aligned with the bearing on said back, and means to secure said member to the bearing on said back.

13. In an automatic tape- and film-reversing reel, a reel back, an axial bearing on said back having a bayonet slot, an auxiliary plate having a spring-pressed axial member, a bearing in said member aligned with the bearing on said plate, and a pin on said member to engage the bayonet slot in the bearing on said reel back.

14. In an automatic tape and film reversing reel, a reel back, an axial bearing on said back, an auxiliary plate having a spring-pressed axial member, a bearing in said member aligned with bearing on said plate, and means on said member to engage the bearing on said reel back to retain the parts in assembled relation.

In testimony whereof I affix my signature.
HARRY M. STEPHENSON.
